FIRE ESCAPE.

No. 299,833.

Patented June 3, 1884.

UNITED STATES PATENT OFFICE.

JORDAN L. MOTT, JR., OF NEW YORK, N. Y.

FIRE-ESCAPE.

SPECIFICATION forming part of Letters Patent No. 299,833, dated June 3, 1884.

Application filed April 5, 1884. (No model.)

To all whom it may concern:

Be it known that I, JORDAN L. MOTT, Jr., of the city and State of New York, have invented an Improvement in Fire-Escapes, of 5 which the following is a correct description.

Ladders have been placed upon the exterior of buildings, such ladders being closed when not in use by one side being raised and the other lowered.

10 My improvement is made for allowing the fire-escape ladder to be opened from either of the upper floors of the building, and for keeping it closed, so that it is not liable to be opened from the outside of the building, and hence 15 cannot be used by burglars, and the case holding the ladder can be ornamental, instead of disfiguring the building, as now usual, by unsightly ladders.

20 In the drawings, Figure 1 is a general view of the ladder at the front of the building, the wall being in section. Fig. 2 shows the lever and rack-bar in larger size. Fig. 3 is a sectional plan with the ladder folded. Fig. 4 is a sectional plan with the ladder open, and 25 Fig. 5 is a partial elevation with the front plate removed.

The plate A is of a more or less ornamental character. It extends vertically at a distance from the wall B of the building—say four or 30 five inches—and it is supported in any suitable manner, preferably by bolts c, projecting from the building, and provided with nuts at their outer ends to confine the plate to the shoulders upon the bolts. The ladder is made 35 to close in behind this plate A, or to open at one or both sides thereof. The ladder is made of the arms or rungs F, pivoted at g to the back of the plate A, and connected by bolts or rivets i at their outer ends to the vertical 40 tie rod or bar k. The inner end of each rung is made with an arm, f, that is slotted longitudinally near its end.

The rack-bar L is guided in suitable projections or slides, l, at the back of the plate A. 45 They may be tubular castings through which the bolts c pass, if desired, and upon this rack-bar L there are pins or studs o, passing into the slots in the arms f. There may be two ladders, one at each side of the rack-bar, as 50 shown. It will now be understood that when

the rack-bar receives an upward endwise movement the ladders are swung down from the position shown by dotted lines in Fig. 5 to the positions shown in full lines, the rungs assuming horizontal positions, and the pins or 55 studs o reaching the ends of the slotted arms f, so as to retain the ladder-rungs and prevent them swinging below a horizontal position. The ladders are now ready for use, and it is to be understood that they should be placed 60 between the windows, so that they can be reached from either window and used for descending or ascending. The rungs of the ladder are sufficiently distant from the surface of the building to give ample room for the feet. 65 When the ladders are open for use, the leverage of the rungs will be sufficient to prevent the weight of the rack-bar, as it hangs upon the inner ends, closing the ladders; but as the 70 said rack-bar is moved endwise and downwardly the ladders are closed, and their weight no longer tends to lift the rack-bar; hence the ladders are not easily opened from outside the building, because of the weight of the rack-bar. I however provide a lever, P, with a 75 segmental rack at the end next to the teeth q upon the rack-bar, and I pivot the same at r and introduce such lever into recess in the wall of the building, there being a hole in the wall for the segmental rack to pass through; 80 and it is best to place one of these levers and racks at each floor of the building, and to suitably incase the opening in the wall, so that the lever will be out of the way; but in case of necessity the fire-escape ladders are 85 instantly spread for use by moving either one of such levers from within the building and lifting the rack-bar L endwise, so as to throw out the ladder-arms and cause them to fall into position for use.

90 At each edge of the front plate, A, there is a narrow folding shutter, t, hinged to the said front plate and drawn inwardly to place, as seen in Fig. 3, by a spring, so as to close in and protect the ladders from atmospheric influences. These shutter-strips, however, are pushed open automatically by the ladders as 95 they are spread.

I claim as my invention—

1. The combination, with the stationary 100

plate A, of the ladder-arms F, pivoted to said plate, and having slotted inner ends, the vertical rack-bar L, with studs entering such slotted ends, and mechanism for moving the 5 rack-bar endwise to open or close the ladders, substantially as set forth.

2. The combination, with the rack-bar L, of the lever P, for moving the same endwise, the pivoted arms forming the ladder-rungs, 10 the bar k, connecting the outer ends of the rungs, and the connections between the pivoted arms and the rack-bar, substantially as set forth.

3. The combination, with the plate A, of the shutter-strips t, hinged to such plate, the 15 pivoted arms forming the ladder, the rack-bar and supports for the same, and the levers for giving end motion to such rack-bars, said levers acting in openings provided in the wall of the building, substantially as set forth. 20

Signed by me this 1st day of April, A. D. 1884.

JORDAN L. MOTT, JR.
